DESIGN FOR AN EXERCISER

Orville Stam, Los Angeles, Calif.

Application July 10, 1935, Serial No. 57,586

Term of patent 14 years

To all whom it may concern:

Be it known that I, Orville Stam, a citizen of the United States, residing at 6114 South Hoover Street, Los Angeles, in the county of Los Angeles and State of California, have invented a new, original, and ornamental Design for an Exerciser, of which the following is a specification, reference being had to the accompanying drawing, forming a part thereof.

The figure is an elevational view of an exerciser, showing my new design.

I claim:

The ornamental design for an exerciser, substantially as shown.

ORVILLE STAM.
